Primary Examiner—Cynthia M Chin*(74) Attorney, Agent, or Firm*—Knobbe Martens Olson & Bear LLP(57) **CLAIM**

The ornamental design for a paintball loader, as shown and described.

DESCRIPTION

FIG. 1 is a back side perspective view of a paintball loader showing our new design;

FIG. 2 is a back view thereof;

FIG. 3 is a front view thereof;

FIG. 4 is a first side view thereof, the other side being a mirror image of the first side;

FIG. 5 is a top view thereof; and,

FIG. 6 is a bottom view thereof.

The broken line portions of the paintball loader are for illustrative purposes only and are not intended to limit the claimed design to the features shown in broken lines.
